UNITED STATES PATENT OFFICE.

MALCOM WALKER AND EPHRAIM MINER, OF YANKTON, DAKOTA TERRITORY.

PORTABLE BRICK-HACK.

SPECIFICATION forming part of Letters Patent No. 326,812, dated September 22, 1885.

Application filed June 16, 1885. (No model.)

To all whom it may concern:

Be it known that we, MALCOM WALKER and EPHRAIM MINER, citizens of the United States, residing at Yankton, in the county of 5 Yankton and Territory of Dakota, have invented certain new and useful Improvements in Portable Brick-Hacks, of which the following is a specification, reference being had therein to the accompanying drawings.

10 Figure 1 is a perspective view of this device as in use. Fig. 2 is a perspective view of the frame and carriage ready for taking up the hack.

The object of our invention is to provide a 15 means whereby a large number of bricks may be easily carried from place to place in a brick-yard or other place with no more help than is ordinarily employed to carry a much smaller quantity.

20 Another object of our invention is to provide a device for carrying bricks which shall be so efficient as to render the accidental dropping of a brick-hack full of bricks practically impossible.

25 In the usual way of carrying bricks from the yard to the kiln, or vice versa, there is much danger of accidental stumbling, and consequent dropping of bricks, which, besides being the source of much annoyance, is very dis-

30 advantageous, as much time is thus lost, and the loss caused by the breaking of bricks is also considerable. Again, by carrying the bricks in the hands in the old way, all of the strain comes directly on the arms of the carrier, and he can only carry a comparatively 35 small number of bricks, whereas by the employment of our device the same person can carry many times the number which he could carry in his arms or on a hack in his hands,

40 and with absolute safety as regards accidental dropping—first, because the hack, when being carried by our device, is so close to the ground that the fall would cause no material concussion, and, second, because the person 45 using the machine, even if he were to fall, would not drop the bricks, as the machine will support the bricks independent of the operator.

This device is designed especially for handling or moving "green bricks." By any other device for that purpose that we know of,

the green bricks, (that is, the freshly molded,) when taken from the machine, are placed into a flat wheelbarrow and carried to the yard, where they are taken from the wheelbarrow 55 and hacked up. When they are dried they are again loaded on the wheelbarrow to be taken to the kiln. By the present invention they are placed directly from the machine upon the hack and wheeled to the yard, set 60 down, dried, and then taken by the carriage to the kiln. Thereby a large part of the labor in loading and unloading the hack is avoided, and in a large brick-yard at least fifty per cent. of this kind of labor is saved. 65

Having set forth the main object of our invention, we will now proceed to describe it in detail.

It consists in a novel construction, arrangement, and combination of parts, which will be 70 hereinafter explained, and more especially pointed out in the claims.

In the accompanying drawings, A designates the frame, secured together by any suitable number of cross-bars, the front one, a, of which 75 is used as a handle in raising or lowering the frame or moving the carriage. The rear bar, a', has on its outer sides the hooks b, the purpose of which will be described hereinafter. At the rear end of the frame A are two eccentric 80 crank-arms, C C—one on each side—the lower outer ends of which form the axles for the wheels D D.

Extending diagonally downward and backward from the side bars of frame A are the 85 braces E E—one on each side—and from the rear of the same bars are a pair of secondary braces, E' E'—one on each side—extending diagonally downward and forward, and crossing the arms E E at e. This portion of the device 90 we call the "cart" or "carriage." The skeleton frame F, preferably made of strong wire, is hung by its horizontal bar or piece f, or in any suitable way, upon the hooks b on the rear bar of the frame A. Each of the flaring 95 wires or bars f' f' on each side has hooked ends f". These ends are adapted to engage under the projections g on each side of the hack G.

It will be observed that when the device is 100 in the position shown in dotted lines in Fig. 2, the front end of the frame A being raised,

the rear of the frame will be lowered and the frame F will come nearer the ground, and so ready for its ends to be engaged on the side projections of the brick-hack.

5 The operation of this device is as follows: The hack being properly filled or loaded with brick, the carriage is wheeled up to the end of the hack and is moved along over it, the wheels being astride the hack. Then by lifting up 10 the forward part of the frame the ends f^3 of the frame F are lowered and can be engaged under the side projections of the hack. Now, by pressing down on the front bar or handle of frame A, the ends of the longer downward- 15 ly-projecting side bars will be the fulcra on which the frame F will be caused to raise the hack till it swings free from the ground and the load of bricks is in a position to be wheeled away. To unload, reverse the above operation. The ends of the shorter side bars are supports for the frame A when the carriage is not used. By having two braces on each side the frame is very much stronger.

It is evident that in the mere detail of construction there may be many merely mechanical changes in the above construction which will in no manner change the nature or scope of our invention.

We are aware that a hive-truck has been 25 constructed similar to our device—*i. e.*, it was provided with two wheels and a pair of handles. It also had a system of levers which served to facilitate the raising of a hive from the ground and suspending the main part of 30 the weight from the axle; but our device is designed especially for carrying flat brick-hacks, and it is much less complicated, while it ac-

complishes the result aimed at without the employment of any levers except the handles, which serve as a means for steadyng the 40 truck. We therefore disclaim the hive-truck above referred to; and

What we desire to secure by Letters Patent, and what we really do claim, is—

1. In a brick-carrying machine, the combination of the main frame and the eccentric crank-arm with the wheels and suitable supports and supporting-frame for the hack, as set forth. 45

2. In a brick-carrying machine, the combination of the main frame, the wheels, and crank-arms with the hooks $b b$ at the front end of the frame, and frame F, having the hooked ends, as set forth. 50

3. In a brick-carrying machine, the frame, 55 the cross-bars a and a' , the hooks $b b$ on the latter forward of the axle-supports or eccentric arms, and the hooked rods F F, with the arms f^3 , as set forth.

4. In a brick-carrying machine, the main 60 frame having side braces or supports, E E', the latter serving the double purpose of a brace and a supplemental handle, the crank-axes C, the hooks $b b$, and the hooked rods F F, all combined in the manner and for the 65 purpose set forth.

In testimony whereof we affix our signatures in presence of two witnesses.

MALCOM WALKER.
EPHRAIM MINER.
